UNITED STATES PATENT OFFICE.

CHARLES WEBER, OF NEWARK, NEW JERSEY, ASSIGNOR TO PERFEX PRODUCTS CORPORATION, OF NEWARK, NEW JERSEY, A CORPORATION OF NEW JERSEY.

COLLAPSIBLE TUBE.

1,368,589.

Specification of Letters Patent. Patented Feb. 15, 1921.

Application filed May 10, 1918. Serial No. 233,609.

To all whom it may concern:

Be it known that I, CHARLES WEBER, a citizen of the United States, and resident of Newark, in the county of Essex and State 5 of New Jersey, have invented certain new and useful Improvements in Collapsible Tubes, of which the following is a specification.

My invention relates to improvements in 10 collapsible tubes adapted to contain liquid, paste, powder or the like, and my invention pertains particularly to improved means for permanently and securely closing the usual charging end of the tube, that is to say, 15 the end opposite the outlet or nozzle through which the contents are to be discharged.

In carrying out my invention I fold the 20 end portion of the tube to be closed to provide a hook-like projection, and I provide 25 a clip having a main body or back portion and two longitudinal folds that provide an inner member and an outer member, the inner member being spaced from said back portion and said outer member being spaced 30 from the inner member. When the clip is on the tube the folded hook-like projection of the tube will be received between said back portion and said inner member of the clip, and the side portion of the tube end 35 will be received between the two members of the clip in such position that the edge of the inner member enters the bight of the hook-like folded projection of the tube. When the parts are thus assembled, the clip may be 40 compressed to squeeze and grip the adjacent portion of the tube with the result that the clip and tube will remain securely attached together and pulling of the clip from the tube will be prevented. The clip may be 45 made of suitable stiff metal so as to retain its folded compressed form on the tube.

The clip is so organized that it may be 50 slid in the direction of its length upon the folded end portion of the tube so that the hook-like projection of the tube may slide between the fold and the back of the clip for properly positioning the clip on the tube, and then said parts may be pressed together as stated.

55 Reference is to be had to the accompanying drawings forming part hereof, wherein, Figure 1 is a perspective view of a collapsible tube ready to receive my improved

clip; Fig. 2 is a perspective view of said clip; Fig. 3 is an enlarged fragmentary detail of a portion of Fig. 1, showing assemblage of the tube and clip; Fig. 4 is an enlarged side view illustrating a portion of the tube and clip attached thereto; Fig. 5 is an enlarged edge view of the clip and 60 Fig. 6 is an enlarged section on the line 6, 6, in Fig. 4.

Similar numerals of reference indicate corresponding parts in the several views.

In the accompanying drawings the number 1 indicates a collapsible tube of any suitable or well known construction, which is adapted to contain liquid, powder, paste and the like in an ordinary manner. The material of the tube includes pyroxylin or 70 similar material and it is capable of being rolled or folded but its surface is so smooth that an ordinary metal clip such as used on metal tubes can not secure a sufficiently firm grip to be held in place by frictional 75 engagement where pressure is applied tending to move it. The tube may be provided with any suitable outlet neck 2 and a removable cap 3. The opposite end of the tube may be open as customary for charging, and 80 after the tube is charged its opposite walls at the open end are to be brought together, and said end portion is then folded at least once to form the hook-like projection 4 extending transversely along the main end 85 portion 5 and spaced therefrom a slight distance, and extending in the direction of the tube. My improved clip is indicated generally at 6 and comprises a suitable piece of sheet metal, (preferably of relatively stiff 90 metal) folded twice upon itself on one side providing the main or back portion 7, the inner member 8 spaced therefrom and extending from one edge of the back and the outer member 9 spaced from the member 8, 95 and extending from the other edge of the back. Said members extend from the back 7 in opposite directions, substantially parallel to the back and to each other, and the member 8 is between the back 7 and the 100 member 9. The back 7 and members 8 and 9 are in such relation as to receive the parts 4, 5, of the tube therebetween as illustrated in Figs. 3, 4 and 6. The inner edge 8^a of folded member 8 of the clip is adapted to 105 fit in the bight 4^a of the folded end of the

tube, while the projection 4 is in the space 10 between the back 7 and member 8 of the clip, the portion 5 of the tube being received in the space 11 between the members 8 and 5 9 of the clip.

The clip having been made in the form described and the tube having been charged and its end portion folded, to produce the hook-like projection 4, they may be assembled by sliding the clip lengthwise along the folded end of the tube in such a manner that the portion 4 of the tube will enter space 10 and the portion 5 of the tube will enter the space 11 of the clip, and then when the clip 10 has been brought to desired position relatively to the width of the tube the clip may be squeezed or compressed firmly against the material of the tube, so that the hook-like projection 4 will be compressed between 15 the member 8 and back 7 of the clip and the part 5 of the tube will be compressed between members 8, 9, of the clip. By the means described an air-tight and leak-proof closure is made at the end of the tube, and 20 25 the clip will not be pulled off the tube in use because of the interlocking of the member 8 of the clip in the bight 4^a of the tube, and the squeezing or compressing together of the parts, since the clip will not unroll because of its flatwise compressed condition 30 35 along the folded edges thereof.

While my improved clip may be used upon collapsible tubes made of metal, of any well known variety in common use for such purpose, my invention is particularly applicable to tubes made of or comprising non-ductile material, such as pyroxylin, of sufficient thinness to be folded and rolled, which tube when folded and provided with a bight, as 40 45 at 4^a, tends to remain in a set and folded condition, the material of the tube having a certain amount of stiffness as compared to the ductility of collapsible tubes of lead or alloy metal.

My improved form of clip is cheap to manufacture, since the clips can be made readily by machinery and the assemblage of the clips and tubes together is inexpensive. My improved form of clip is particularly 50 55 adapted to tubes charged with liquid, since the folded end of the tube has the advantage of serving to prevent the escape of the liquid while the clip is being applied to the tube, as distinguished from the known manner of applying a flat strip to the open end of a tube and then rolling the end of the tube and strip together while the liquid is in the tube.

Having now described my invention what I claim is:

1. A collapsible tube having a fold at its end providing a projection extending transversely and back along the tube, and a clip upon the tube having a flat back and a flat inner and a flat outer member extending 60 65 from the back, the projection of the tube being between the back of the clip and its inner member, and the adjacent body portion of the tube being between the said members of the clip, the edge of the inner member of 70 the clip opposing the bight of the fold of the tube being smooth, said clip being compressed upon the adjacent portions of the tube.

2. A collapsible tube comprising non-75 ductile flexible material having a flat transverse fold at its end providing a projection extending back parallel to the flat portion of the tube and spaced therefrom, and a clip upon the tube having a flat back provided with members forming integral continuations thereof at opposite ends spaced therefrom and from each other in parallel relation on one side of the back and extending in opposite directions, said projection 80 85 from the tube being located between the back and one of said members and the edge of said member at the bight of the fold being smooth and the adjacent body portion of the tube being between said members, said 90 clip being compressed upon the adjacent portions of the tube to form a liquid tight joint.

3. In a device of the class described the combination with a collapsible tube having 95 its walls brought together in flat form at one end and bent back upon itself on a transverse line, of a metal clip embracing and clamping said folded end comprising an end portion with a smooth edge and 100 slightly rounded corners fitting between the two portions of the folded tube, an intermediate portion bent across the end of the folded over portion of the tube and back flat against it and an end portion bent across 105 the fold in the tube and flat against the flattened side of the tube, the three sections of the clip being pressed flat toward each other and against the inclosed folded tube to serve as a lock and clamp forming a 110 water tight joint.

Signed at New York city, in the county of New York and State of New York, this 3rd day of May, A. D. 1918.

CHARLES WEBER.
